CLAIM

The ornamental design for a coffee table as shown and described.

DESCRIPTION

FIG. 1 is a front, right and top perspective view of a coffee table showing my new design;

FIG. 2 is a front elevational view thereof;

FIG. 3 is a rear elevational view thereof;

FIG. 4 is a left view thereof;

FIG. 5 is a right view thereof;

FIG. 6 is a top plan view thereof;

FIG. 7 is a bottom plan view thereof;

FIG. 8 is a rear, left and bottom perspective view thereof;

FIG. 9 is front, right and top perspective view in an extended configuration;

FIG. 10 is a front elevational view in an extended configuration;

FIG. 11 is a rear elevational view in an extended configuration;

FIG. 12 is a left view in an extended configuration;

FIG. 13 is a right view in an extended configuration;

FIG. 14 is a top plan view in an extended configuration;

FIG. 15 is a bottom plan view in an extended configuration; and,

FIG. 16 is a rear, left and bottom perspective view in an extended configuration.

The evenly dashed broken lines illustrate portions of the article that form no part of the claimed design.

1 Claim, 16 Drawing Sheets
